UNITED STATES PATENT OFFICE.

JAMES L. TUFFLEY, OF ATTLEBORO, MASSACHUSETTS, ASSIGNOR TO THE JAMES E. BLAKE COMPANY, OF ATTLEBORO, MASSACHUSETTS, A CORPORATION OF RHODE ISLAND.

CIGARETTE-CASE.

1,195,629.

Specification of Letters Patent. Patented Aug. 22, 1916.

Application filed April 1, 1916. Serial No. 88,189.

To all whom it may concern:

Be it known that I, JAMES L. TUFFLEY, a citizen of the United States, residing at Attleboro, in the county of Bristol and State 5 of Massachusetts, have invented a new and useful Improvement in Cigarette-Cases, of which the following is a specification.

This invention relates to certain new and useful improvements in cigarette cases, and 10 the primary object of the invention is to provide a case in which the cigarettes are carried by a movable holder, which latter upon release of the usual catch for the case is automatically projected out from the case 15 in a position to enable free and easy removal of the cigarettes.

A further object of the invention is to provide a holder which is also automatically moved into the case by the act of closing the 20 case and without being touched by the user or operator.

A still further object of the invention is to provide a holder which projects the cigarettes from a side of the case, and at a distance 25 from the latter so as to more easily enable the cigarettes to be removed.

Still further, the invention aims to provide a case which can be opened and closed with the use of but one hand.

30 In the drawings—Figure 1 is a perspective view of the invention showing the case in open position and the holder projected therefrom. Fig. 2 is an end elevation of Fig. 1. Fig. 3 is a plan view, partly in section, showing the holder when in housed position within the case. Fig. 4 is a section on the line 4—4 of Fig. 3. Fig. 5 is a similar view on the line 5—5 of Fig. 3. Fig. 6 is an end elevation illustrating the case as in 35 the act of manipulation by use of but one hand, and Fig. 7 is a detail perspective view of the holder support.

The case embodies a front 1 and back 2 hinged thereto and secured by means of the 40 usual latch or catch 3, the hinge being of the customary type of spring hinge which automatically separates the front and back upon release of the catch.

The holder embodies a substantially U- 45 shaped frame 4 having a central partition 5 provided with struck-out projections 6 and similar bent projections 7 which form cigarette seats on the opposed faces of the partition. Hinged arms 8, the hinges being of

the spring type retain the cigarettes in their 55 seats.

The holder is connected to a T-member 9 by means of a spring hinge 10, the hinge being secured to the top of said member while the web of the member is formed with 60 a knuckle 11 which pivotally receives the pintle pin 12 of the hinge 13 of the front and back 1 and 2 respectively. The member 9 is located adjacent a side of the case so that when the holder is projected out 65 from the case it will present all of the cigarettes in a position where same can be removed, or the holder replenished without interference from the case.

The front and back are provided with 70 the inwardly extending marginal flanges 14 and the holder is positioned so that when the case is in the open position depicted in Fig. 1, of the drawings, the base of the holder will be engaged with these flanges 14 75 and be supported thereby. When the case is closed, the flanges 14 will ride upon the base of the U-frame of the holder and will move the latter into the case, and when the catch 3 is released, the spring of the hinge 80 13 will force the front and back apart, and be assisted by the action of the holder, which latter under the influence or impulse of the spring of the hinge 10, will be itself moved outwardly from the 85 case and in its said movement will, by bearing against the flanges 14, move the front and back apart and hold same apart.

Referring to Fig. 6 of the drawings, it will be noted that the case is illustrated as 90 in use with one hand, the case being shown as in the act of being closed. In opening of the case, same is held in one hand, and the thumb moved to release the catch, whereupon the springs of the several hinges act 95 to move the case front and back, and the holder to the position shown in Fig. 1.

Extending inwardly from the flanges 14 at an angle thereto are inclined guides, which function to move the holder inwardly 100 following initial inward movement imparted by the flanges 14 riding on the opposite side edges of the base of the U-frame 4 of the holder, so as to bring the holder fully within the inner edges of the flanges 14 105 thereby to not interfere with free closing of the front and back and their securement by the catch 3. This function of the guides 15

can be clearly viewed in Fig. 3, in which latter the holder is shown in the position it occupies when the case is closed, and in which it will be apparent that the holder is held well away from the flanges 14, and in fact spaced from the entire four bounding flanges of the front and back.

The operation is as follows: The case is held as depicted in Fig. 6, and the thumb 10 moved to release the catch following which the hand is moved to the position illustrated in said figure, whereupon the spring of the hinge 13, acts to move the front and back apart and at the same time the spring of the hinge 10 moves the holder out from the case. This outward movement of the holder also assists in the stated separating movement of the front and back, since the opposed side edges of the base of the U-shaped frame 4 of the holder engage the flanges 14 of the front and back and force these parts away from each other. In closing of the case, the front and back are moved to approach each other, the flanges 14 riding on or against the opposed side edges of the base of the holder, forcing the latter inwardly against the action of the spring of hinge 10, and finally the guides 15 enter into action and move the holder away from the edges which have initially given the holder its inward movement.

It will thus be apparent from the foregoing that the holder is automatically projected out from the case and likewise moved into the case by the mere action of opening or closing the case, and that the cigarettes are thus held in a position away from the case so as to be easily accessible for expeditious removal, and replenishment as well.

Having thus described my invention, what I claim as new and desire to secure by Letters Patent is—

1. In combination with a cigarette case including a hinged front and back, a member secured to the hinge pintle, a holder, a spring hinge connected to the holder and member, and flanges on the front and back for engagement with the opposed side edges of the base of the holder for automatically moving the holder into the case upon closing of the same.

2. In combination with a case having a hinged front and back, a holder in hinged connection with the case hinge, means for moving the holder out from a side of the case upon opening of the same, and flanges on the case for engagement with the holder for moving the latter into the case upon closing of the case.

3. In combination with a case having hinged front and back, a member pivoted to the hinge pintle of the case, a holder hinged to the member at a side of the case, means for tensioning the holder so that upon opening of the case the holder will be projected

out from a side of the case, and means associated with the case for automatically moving the holder into the case upon closing of the same.

4. In combination with a case having a cover, a holder formed to removably hold cigarettes, and means operating independent of the cover whereby upon opening of the latter the holder will be automatically projected out of the case. 75

5. In combination with a cigarette case having a cover, a normally tensioned cigarette holder held by the case and cover therewithin and means which upon release of the cover causes the holder to be bodily moved entirely without the case to allow the cigarettes to be removed therefrom. 80

6. In combination with a case having a hinged cover, an article holder completely housed in the case, and means whereby upon opening of the cover the holder is projected from the case at right angles to the plane in which the cover moves in a position to allow the article to be removed therefrom. 85

7. In combination with a case having a latched cover and adapted to be held in and operated with one hand, a cigarette holder in the case movable at right angles to the direction of movement of the case and cover, and means whereby upon release of the latch the holder will be automatically projected out from a side of the case. 90

8. In combination with a case having a cover, a holder normally disposed within the case and spring means to tension the holder and adapted when the cover is released to cause the holder to be projected out of the case in a plane at right angles to the plane of movement of the case and cover. 100

9. A case having a cover and adapted to be held and operated with one hand, an article holder connected to the case and movable at right angles to the plane of movement of the cover, and means whereby upon release of the cover the holder will be automatically moved out of a side of the case. 105

10. A case having a cover, a holder in the case movable upon opening of the cover out of the case, means to move the holder out of the case upon release of the cover, and rigid means on the case and cover to move the holder into the case upon closing of the cover. 115

11. A case having a cover, a holder in the case movable upon opening of the cover out of the case, means to move the holder out of the case upon release of the cover, and means on the case and cover to engage opposite sides of the holder to move the latter into the case upon closing of the cover. 120

12. A case having a hinged cover, a holder, and means to move the holder out of the case when the cover is opened, said case and cover having rigid parts engaging 130

opposite sides of the holder so that upon closing of the cover the holder will be automatically moved into the case.

13. A case having a hinged cover and adapted to be held in one hand with the fingers engaging one part and the thumb the other part, a holder in the case, and means whereby upon release of the cover the holder will be automatically moved at right angles to the plane of the cover movement and projected out from a side of the case in the space between the thumb and fingers so as to present the article carried by the holder vertically.
14. A case having a hinged cover and a

cigarette holder the latter when in the case and in conjunction with the latter holding the cigarette parallel to the plane of the hinge, and means to automatically project the holder out of the case when the cover is opened and to dispose the cigarettes in a plane at right angles to the plane of the hinge.

In testimony whereof I have signed my name to this specification in the presence of two subscribing witnesses.

JAMES L. TUFFLEY.
